DESIGN FOR A HANDKERCHIEF

M. Joseph Rosen, New York, N. Y.

Application August 20, 1936, Serial No. 64,486

Term of patent 3½ years

To all whom it may concern:

Be it known that I, M. Joseph Rosen, a citizen of the United States of America, residing in Manhattan, county of New York, and State of New York, have invented a new, original, and ornamental Design for a Handkerchief, of which the following is a specification, reference being had to the accompanying drawing, forming part thereof, wherein,

The figure is a plan view of a handkerchief showing my new design.

As shown, the handkerchief is folded both longitudinally and transversely through the center portions giving it the appearance of irregularities of design. This was done, however, for convenience of illustration.

I claim:

The ornamental design for a handkerchief, substantially as shown, and described.

M. JOSEPH ROSEN.
